COMBINED BAR SPONGE AND COVER FOR A CAN AND BOTTLE OPENER

Elmer Haslett, Forest Hills, N. Y.

Application September 13, 1956, Serial No. 42,927

Term of patent 14 years

(Cl. D44—29)

Fig. 1.

Fig. 2.

Fig. 1 is a perspective of a combined bar sponge and cover for a can and bottle opener embodying my design; and

Fig. 2 is a bottom perspective of the same.

The dotted line representation of an opener is for illustration purposes, and the drawing is stippled to indicate variegated contrasting colors.

I claim:

The ornamental design for a combined bar sponge and cover for a can and bottle opener, as shown and described.
